(57) **CLAIM**

The ornamental design for a bottle, as shown and described.

DESCRIPTION

FIG. 1 is a perspective view of the bottle showing our new design;

FIG. 2 is a front elevational view thereof;

FIG. 3 is a side elevation of the bottle, the opposite side is the same except for the screw threading on the neck;

FIG. 4 is a top plan view thereof; and,

FIG. 5 is a bottom plan view thereof.

The portion of the threaded neck that is not shown in the drawings does not form part of the claimed design.
